NOZZLE ADJUSTMENT FOR SUCTION
CLEANERS

Harry B. White, Canton, Ohio, assignor to The
Hoover Company, North Canton, Ohio, a cor-
poration of Ohio

Application March 16, 1948, Serial No. 15,067

8 Claims. (Cl. 15—358)

1

The present invention relates to suction cleaners and more particularly to an automatic nozzle adjustment therefor in which it is impossible to use the cleaner without properly adjusting the nozzle.

As is well known a suction cleaner nozzle must be properly positioned with relation to the surface covering being cleaned. That is, the position should vary with variations in the type of the carpet being cleaned and should be further varied if the cleaner is being used on a bare floor.

When used on floor coverings the wheels sink into the nap of the floor covering and unless some change is made in the nozzle adjustment the nozzle will be too high when used on floor coverings having short or stiff nap and too low when used on floor coverings having long or soft nap. For ideal operations a nozzle should be supported a fixed distance above the surface of the nap of the floor covering. The floor covering will then be drawn up against the suction cleaner and subjected to nearly constant suction.

Suction cleaners are usually stored with the handle in upright or storage position and some means may be provided to lock the handle in storage position. When the cleaner is to be used the user may carry the cleaner to the room being cleaned by the handle or the handle may be moved from storage position and the cleaner propelled to the room.

According to the present invention an automatic mechanism is provided for properly adjusting the nozzle for the particular type of surface being cleaned by which the operator is compelled to go through the necessary operations to properly adjust the nozzle.

Specifically according to the broadest aspects of this invention, the handle is locked in storage position and manually operable means is provided for both initiating the action of the nozzle adjusting mechanism and releasing the handle from locked position in which the handle cannot be released from locked position unless the preliminary action of the nozzle adjusting mechanism is also initiated.

Also according to the preferred modification the nozzle adjusting mechanism is such that the adjustment of the nozzle is completed by the normal movement of the propelling handle as the cleaner is moved back and forth over the surface being cleaned.

According to this invention a feeler or gauging means is provided which drops to the surface upon which this cleaner is positioned upon re-

2

lease of the handle from storage position and the wheels are moved downwardly relative to the cleaner body to raise the nozzle from the floor. The feeler sets a mechanism into a definite position, depending upon the type of surface upon which the cleaner is positioned, which position fixes the final position of the nozzle relative to the surface to be cleaned. The final adjusting action is completed by the normal movement of the propelling handle in propelling the cleaner back and forth over the surface. The amount the nozzle is adjusted by the normal movement of the handle depends entirely upon the position of the feeler relative to the supporting wheels which in turn is dependent upon the type of surface upon which the cleaner is placed.

The mechanism is so made that the amount of movement of the nozzle by the normal movement of the handle during cleaning is greatest when the handle is released while the cleaner is positioned on a bare floor and the least when the handle is released while the cleaner is positioned on the thickest carpet having the softest nap.

More specifically the manually actuated lever which releases the handle from its locked vertical position moves the wheels downwardly relative to the cleaner body to raise the nozzle upwardly relative to the surface upon which the cleaner is positioned and in doing so releases a selector from the wheel adjusting mechanism and permits the feeler to contact the surface upon which the cleaner is positioned under the influence of a light spring. The feeler then resets the selector relative to the wheel adjusting mechanism depending upon the type of surface upon which the cleaner is positioned which will determine the final position of the nozzle relative to the surface when the adjustment is completed. The normal movement of the handle in propelling the cleaner back and forth will return the wheel adjusting mechanism toward its original position in a step-by-step movement. If the cleaner is positioned on a thick carpet only a single reciprocation may be necessary but if it is positioned on a thin carpet or upon a bare floor two or more reciprocations may be necessary to complete the adjustment.

According to a modification of this invention the manually actuated lever which releases the handle from its locked vertical position releases a clutch or selector mechanism which permits the wheel to sink into the nap of the carpet while the nozzle acts as a feeler or gauging means and is positioned upon the surface of the carpet. The wheels are spring pressed downwardly and

will sink various distances into the carpet depending upon the type of carpet upon which the cleaner rests. When the manually actuatable lever is released for movement to its original position the clutch or selector is reset at some point, depending upon the position of the wheels relative to the nozzle when the nozzle is resting against a supporting surface, so as to raise the nozzle from the surface to its proper operative position.

Other objects and advantages of this invention will become apparent as the description proceeds when taken in connection with the accompanying drawings in which:

Figure 1 is a side view of a suction cleaner constructed in accordance with the present invention with certain parts broken away;

Figure 2 is a bottom view of the cleaner illustrated in Fig. 1;

Figure 3 is a partial side view of the cleaner illustrated in Fig. 1 in the first stage of the adjustment of the nozzle, the foot pedal being depressed and the handle being moved from the storage position to the lower end of its working range;

Figure 4 is a view similar to Fig. 3 showing the relationship of the parts after the machine has been reciprocated forwardly and rearwardly and the nozzle has been properly positioned relative to the supporting surface;

Figure 5 is a transverse section looking in the direction of the arrows upon the line 5—5 of Fig. 4;

Figure 6 is a sectional view on the line 6—6 of Fig. 5;

Figure 7 is a side elevational view of a suction cleaner with certain parts broken away showing a modified form of this invention; and

Figure 8 is a view showing the modification of Fig. 7 with the nozzle positioned in its downward position against a surface, covering preparatory to the final adjusting action.

This application is a continuation in part of my copending application for U. S. Letters Patent Ser. No. 500,894, filed September 2, 1943, which was formally abandoned in favor of this application on April 12, 1948. Figures 1 to 6 of this application are duplicates of Figs. 1 to 6 of my former application, above referred to, while Figs. 7 and 8 have been added.

This invention is applied to a suction cleaner having the handle pivoted to the rear of the casing and comprises a main casing 1 including a suction nozzle 2 having front and rear surface contacting lips 3 and 4 respectively. The nozzle 2 is connected by an air passage 6 to the fan chamber 7 having a fan 8 therein carried by the shaft 9 of a motor which is housed within a motor hood 11 positioned on the top of the main casing 1 directly above the fan chamber 7.

The fan 8 exhausts into an exhaust passage 12 extending rearwardly from the chamber 7 to an exhaust outlet to which a filter bag 14 is attached by clamping nut 16. An agitator 18 positioned in the nozzle 2 is rotated by a belt 19 extending about the extended end of the shaft 9 which is formed as a pulley for that purpose.

The cleaner is supported by rear wheels 21 secured to the main casing 1 near the rear end thereof by a U-shaped bracket 22 and by front wheels 23 carried by the offset ends of a rock shaft 24 pivotally attached to the front of the casing 1 immediately to the rear of the nozzle 2. The rock shaft 24 is adapted to be rotated in ad-

justing the front wheels 23 in a manner to be explained hereinafter.

A propelling handle 26 is pivotally attached to the rear upper side of the casing 1 immediately above the exhaust passage 12 by an inverted U-shaped bracket 27 and by the pivot pin 28. A coil spring 29 (Fig. 2) surrounds the pivot pin 28 and counterbalances the weight of the handle 26 when it is moved from its vertical storage position.

The handle 26 is positively locked in its vertical storage position by a roller detent 33 on the end of a detent arm 34 pivoted at 36 to a bracket 37 (Figs. 5 and 6) attached to the main casing 1 which cooperates with notches in a sector 31 rigidly attached to the lower end of the handle 26 by a support 32 (Figs. 2 and 5). Detent arm 34 is biased clockwise by a spring 38 surrounding the pivot pin 36 and having one end anchored to the bracket 37 by a fixed pin 39 and the other to the leg 41 of the detent arm 34, the leg 41 being rigid with the arm 34 and movable therewith. The spring 38 holds the roller detent 33 in the notches of the sector 31 so that the handle 26 cannot be removed from its vertical storage position until released therefrom by a mechanism which will be presently described. When the roller detent 33 is positioned on the sector 31 between the notches, which determine the normal working range of the handle 26, the handle cannot be removed therefrom without the application of considerable force thereto.

A plate 43 is pivoted by pin 44 to a vertical wall 46 (Fig. 5) integral with the main casing 1. The plate 43 carries a foot pedal 42 and a trip pin 47 (Figs. 2 and 3) adapted to cooperate with the leg 41 of the detent arm 34 in a manner which will be described hereinafter.

A feeler 53 is pivoted to the underside of the casing 1 by means of the downwardly extending bracket 54 and pivotally carries a selector sector 51, the outer end of which has a plurality of notches therein which cooperate with one of the offset ends of the rock shaft 24 as will later become apparent. The feeler 53 is normally biased to its downward position by a light spring 56 and its upper limit of travel is determined by the stop 58 extending downwardly from the casing 1. The downward movement of the selector sector 51 relative to the feeler 53 is limited by the pin 57 carried by the feeler 53 forwardly of the pivot point of the selector 51. As shown in Fig. 2 the bottom of the feeler 53 is made comparatively wide and slopes upwardly toward the rear so that it will ride on top of the nap of a rug or carpet. The spring 56 is comparatively weak so that the above will be true even though the cleaner is propelled back and forth with the feeler 53 in its downward position.

The feeler 53 is normally held against the stop 58 by the force of a coiled spring 59 connected between the offset ends of the rock shaft 24 and the underside of the casing 1 and by the weight of the cleaner both tending to rotate the wheels 23 upwardly toward the casing 1.

One end of a connecting rod 61 is attached to one of the crank arms of the rock shaft 24 and its other end enters a socket 62 carried by an eccentric strap 63 surrounding an eccentric 64 formed integrally with the plate 43 which also has a toothed sector 66 formed integrally therewith. A pawl 67 is pivoted at 68 to the handle sector 31 at a point spaced forwardly from the pivot pin 28 of the handle 26. A spring 69 surrounds the pivot pin 68 of the pawl 67 and biases

the pawl counter-clockwise so as to bring the end 71 of the pawl 67 into contact with the teeth of the sector 66 unless held therefrom. A pin 73 on the detent arm 34 engages the pawl 67 to hold the end 71 of the pawl 67 away from the teeth of the sector 66 when the handle 26 is in vertical storage position as shown in Fig. 1.

A barrier plate 76 (Fig. 6) is slidably mounted in the guide 77 on the side of the plate 43 and is held retracted to the left as viewed in Fig. 6 by a spring 78 to expose the teeth of the sector 66. A lever 81 pivoted to the plate 43 is connected to the barrier plate 76 and has a portion overlying the foot pedal 42 for a purpose which will be described presently.

Operation of Figures 1 to 6

Assume that the cleaner is positioned on a carpet or other surface with the handle locked in storage position as viewed in Fig. 1. The nozzle 2 may or may not be positioned in proper relationship to the carpet for optimum cleaning effectiveness. In Fig. 1 the nozzle 2 is shown in an improper relationship being too close to the carpet.

The operator will press downwardly on the plate 81 which will first move the barrier plate 76 to the right as viewed in Fig. 6 so as to cover the teeth of sector 66. When the plate 81 engages the foot pedal 42 the plate 43 will be rotated clockwise as viewed in Fig. 1. The pin 47 on plate 43 will first engage the leg 41 of detent arm 34 and move the arm 34 counter-clockwise and release the roller detent 33 from the notch in the handle sector 31. The handle 26 may then be pivoted rearwardly which will raise the pawl 67 upwardly, its end 71 being prevented from contact with the teeth of the sector 66 by the barrier plate 76.

Continued movement of the pedal 42 downwardly will rotate the eccentric 64, which is integral with the plate 43, clockwise relative to the eccentric strap 63. This will cause the connecting rod 61 to be moved to the left which will rotate the rock shaft 24 clockwise so as to move the wheels 23 downwardly relative to the casing 1 and raise the nozzle 2. During this movement the notch of the selector 51 which was engaged with the end of the axle of the rock shaft 24 will be disengaged and the feeler 53 will pivot clockwise under the bias of the spring 56 until it contacts the surface of the carpet, the selector 51 being held elevated by contact with the pin 57 on the feeler 53. This position is shown in Fig. 3. If the rug is thick and has a soft nap the wheels 23 will sink into the nap so as to be positioned below the bottom edge of the feeler 53. If the cleaner is positioned on a bare floor the wheels will be even with the bottom edge of the feeler 53. This will condition the selector 51 so that the axle of rock shaft 24 is positioned to engage a high notch of the selector 51 if the cleaner is on a thick carpet and a low notch if the cleaner is on a bare floor. This position will determine the final position which the nozzle will take relative to the surface upon which the cleaner rests when the adjustment is completed. It is to be noted that the distance between the axle of the rock shaft 24 and the lower notches of the selector 51 is greater than between the axle and the higher notches.

The pressure is then released from the plate 81 permitting the spring 78 to move the barrier plate 76 backwardly so as to clear the teeth of the sector 66. Movement of the handle 26 from

the vertical storage position of Fig. 1 has previously moved the pawl 67 upwardly into a position so that its lower end 71 may engage the teeth of the sector 66 when the handle is moved upwardly again.

The cleaner may now be moved back and forth over the surface being cleaned in a manner to perform its cleaning function and the nozzle will be automatically adjusted into its proper position for optimum cleaning effectiveness.

As the cleaner is moved back and forth the handle will be moved upwardly and downwardly relative to the cleaner body being moved upwardly as the cleaner is drawn rearwardly and downwardly as the cleaner is pushed forwardly. Since the feeler 53 has a flat inclined bottom edge and the spring 56 is comparatively weak the feeler will merely glide along the surface whether the cleaner is positioned on a thick carpet or a hard surface. Upon upward movement of the handle 26 the pawl 67 will be moved downwardly and its end 71 will engage one of the teeth of the sector 66 and rotate the eccentric 64 counter-clockwise. This will cause the socket 62 to move to the right followed by the connecting rod 61 under the bias of the spring 59 and the weight of the cleaner. This will cause the wheels 23 to move upwardly relative to the casing 1 and the nozzle 2 to move downwardly toward the surface upon which the cleaner rests.

If the cleaner is positioned on a very thick carpet one raising of the handle 26 may move the wheels 23 sufficiently to engage the axle of the rock shaft 24 with one of the notches in the selector 51 in which event the adjustment will be completed and locked in that position. If the movement of the rod 61 was sufficient the weight of the cleaner and the force of the spring 59 will move the selector 51 rearwardly and pivot the feeler 53 counter-clockwise to raise it from the surface upon which the cleaner is positioned against the stop 58.

If the cleaner is positioned on a thin carpet or on a bare floor one or more reciprocations of the handle 26 may be necessary to engage the axle of the rock shaft 24 with the proper notch in the selector 51. However, regardless of the type of surface upon which the cleaner is positioned that engagement will eventually take place and the adjustment of the nozzle made as above described by the normal movement of the cleaner over the surface being cleaned and in delayed relationship to the release of the handle from storage position.

Continued reciprocation of the handle 26 will reengage the end 71 of the pawl 67 with tooth after tooth of the sector 66 and rotate the eccentric 64 counter-clockwise until the axle of the rock shaft 24 becomes locked with the selector 51 as above described after which the socket 62 will merely move to the right relative to the end of the connecting rod 61 and the adjustment of the nozzle will not be altered. After the end 71 of the pawl 67 engages the upper tooth of the sector 66 no further movement will occur.

In normal use the cleaner is usually placed in storage position before the cleaner is moved to another room having a different type of floor covering. Thus, in normal use the adjustment must be made for each type of floor covering to be cleaned before the handle can be moved from storage position. However, should the operator move the cleaner to another type of surface without moving the handle to storage position it is only necessary to again press downwardly on the

plate 31 and the pedal 42 whereby the nozzle will again be automatically adjusted for optimum cleaning effectiveness for the particular surface being cleaned.

Referring to Figs. 7 and 8 the cleaner is in all respects like that of Figs. 1 to 6, inclusive, except for the nozzle adjustment. Where the parts are the same they have been given the same reference numerals. Only the modified parts will be described.

The handle 82 is pivoted at 83 to the top of the casing 1 as in the first modification. The lower end of the handle 82 is formed in the shape of a sector 84 having protuberances 85 and 86 which determine the limits of the normal working range of the handle. A deep notch 87 is also formed in the sector 84 beyond the protuberance 85 to determine the upright or storage position of the handle.

The sector 84 cooperates with a roller detent 88 carried by the end of a detent arm 89 which is pivoted to the casing 1 at 90 and is spring-biased clockwise by a spring 91. The handle 82 cannot be removed from storage position until the roller detent 88 is positively removed from the notch 87.

A foot pedal 92 is pivoted to the casting 1 at 93 and is spring-biased counter-clockwise against the stop 94 by a spring 95. Rotatably mounted on the pivot 93 of the foot pedal 92 is a brake drum 96, surrounded by a brake band 97, one end of which is attached to the pedal 92 at 98. The brake band 97 is normally held contracted about the drum 96 by a spring 99 which abuts at one end against the end 100 of the brake band 97 and at the other end against a projection 101 integral with the foot pedal 92. A connecting rod 102 is pivoted to the brake drum 96 eccentric to the axis of the drum and at its other end is pivoted to a crank arm 103 of a rock shaft 104 which pivotally carries the front wheels 23 of the cleaner. The rock shaft 104 is spring-biased clockwise by a spring 105 so as to normally bias the wheels 23 downwardly relative to the casing 1. The lower end 106 of the detent arm 89 cooperates with the lug 101 on the foot pedal 92 in a manner to be explained presently.

Operation of Figures 7 and 8

In Fig. 7 the parts are shown in the position they occupy when the handle is in its upright or storage position. The nozzle 2 may or may not be properly positioned for maximum cleaning efficiency. In order to remove the handle 82 from its upright storage position it is necessary to press downwardly on the foot pedal 92 which will immediately begin to move the link 102 to the right and pivot the wheels upwardly relative to the casing 1 against the bias of the spring 105 and permit the nozzle to drop against the nap of the carpet or against any other surface upon which the cleaner rests. Continued depression of the foot pedal 92 will bring the end 100 of the brake band 97 into contact with the stop 94 and loosen the brake band's grip on the brake drum 96. This will permit the spring 105 to move the wheel 23 downwardly so as to penetrate into the nap of the carpet a distance depending upon the type of surface being cleaned. This position is shown in Fig. 8 and preselects the final adjustment of the nozzle 2 above the surface upon which the cleaner rests.

Slight continued depression of the foot pedal 92 will bring the lug 101 into contact with the lower end 106 of the detent arm 89 so as to move it counter-clockwise and release the roller detent 88 from the notch 87 in the sector 84 and permit

the handle 82 to be moved from storage position. Upon release of the foot pedal 92 the spring 95 will return the pedal to its original position. As the end 100 of the brake band 97 moves away from the stop 94 the brake band 97 will be tightened about the brake drum 96 by the spring 99 so that the drum 96 will move with the foot pedal 92 to move the link 102 to the left and the wheels 23 downwardly relative to the casing 1 so as to raise the nozzle 2 above the surface upon which the cleaner rests the correct distance for maximum cleaning efficiency.

In the modification of Figs. 7 and 8 the nozzle lips 3 and 4 constitute the gauging means which preselects the final position of the nozzle 2 relative to the surface upon which the cleaner rests. The wheels 23 are moved downwardly relative to the casing 1 a variable distance dependent upon the type of surface upon which the cleaner rests and are again moved downwardly relative to the casing 1 to raise the casing 1 a fixed distance regardless of the type of surface upon which the cleaner rests.

It is to be noted that according to the modification of Figs. 7 and 8 the adjustment must be made every time the handle is removed from storage position thus assuring that the nozzle will be properly adjusted for maximum cleaning efficiency on all types of surfaces.

While I have shown but two modifications of my invention it is to be understood that these modifications are to be taken as illustrative only and not in a limiting sense. I do not wish to be limited to the particular structure shown and described but to include all equivalent variations thereof except as limited by the scope of the claims.

I claim:

1. A suction cleaner comprising; a body including a nozzle; wheels for supporting said body for movement over a surface with said nozzle positioned at a selected distance above said surface; attaching means for movably securing said wheels to said body; a handle movably attached to said body for propelling said body over said surface; a latch for locking said handle in a vertical storage position; surface gauging means carried by said body so as to be movable into contact with said surface; selector means movably carried by said body and constructed to be positioned by said gauging means; manually actuatable latch release means movably mounted on said body and engageable with said latch and operable to release said handle for movement from vertical storage position and means connecting said latch release means with said wheel attaching means and said selector means and operable upon movement of said latch release means to latch releasing position for moving said wheels relative to said body and for releasing said selector means and gauging means to cause said gauging means to move into contact with said surface and position said selector means, and means operable by movement of said handle to actuate said connecting means to move said wheels to the position selected by said selector means, to relock said selector means and to raise said gauging means from said surface.

2. A suction cleaner comprising; a body including a nozzle; wheels for supporting said body for movement over a surface; a rock shaft for pivotally connecting said wheels to said body; spring means for biasing said rock shaft to move said wheels upwardly relative to said body; a manually actuatable lever pivoted to said body;

an eccentric attached to said manually actuatable lever so as to be moved therewith; a connecting rod; an eccentric strap connecting one end of said connecting rod to said eccentric; the other end of said connecting rod being connected to said rock shaft so as to rotate said rock shaft and move said wheels relative to said body; a handle pivoted to said body for propelling said body over said surface; a selector normally engaging said rock shaft to lock said rock shaft against rotation to position said wheels in a fixed relationship to said body; surface gauging means for positioning said selector relative to said rock shaft; the arrangement being such that movement of said manually actuatable lever rotates said eccentric to move said wheels relative to said body, releases said selector means from said rock shaft, permits said gauging means to move into contact with the surface upon which the cleaner rests to position said selector relative to said rock shafts; and means operable by movement of said handle for rotating said eccentric to move said rock shaft and lock said selector means and position said wheels relative to said body in a position determined by the position of said gauging means.

3. In a suction cleaner, a body including a nozzle, a handle movably secured to said body, supporting means, adjustable means to adjustably secure said supporting means to said body to position said nozzle relative to a surface, a movable element carried by said body and engageable with said adjustable means to lock said supporting means in the final adjusted position, surface gauging means carried by said body for positioning said movable element at varying positions relative to said adjustable means depending upon the type of surface upon which said supporting means rests, manually actuatable means associated with said body, means connected between said manually actuatable means, adjustable means and movable element for releasing said movable element from locking engagement with said adjustable means and for releasing said gauging means for movement into contact with said surface to position said movable element relative to said adjustable means and means responsive to movement of said handle in propelling said body over said surface for reengaging said movable element with said adjustable means and moving said gauging means from contact with said surface.

4. In a suction cleaner, a body including a nozzle, a wheel, mounting means adjustably connecting said wheel to said body, adjustable means to position said mounting means relative to said body and including clutch means to release said mounting means, a surface-contacting feeler to position said adjustable means with said clutch means in open relationship and in accordance with its determination concerning an underlying surface, a handle connected to said body to exert a propelling force thereon, means to retain said handle in a vertical storage position and within a working range, a rotatable eccentric, means actuated by said eccentric to open or close said clutch means, a foot lever to rotate said eccentric in one direction to open said clutch to release said mounting means from said adjustable means, means including means connected to said handle to rotate said eccentric in the opposite direction to close said clutch means to re-establish the control of said adjustable means over said mounting means.

5. A nozzle-height-adjusting mechanism for a suction cleaner comprising a nozzle to be adjusted, a handle pivotally mounted on said

cleaner to swing relatively thereto in its working range adapted for propelling and adjustment of the nozzle and further adapted to be placed into vertical storage position, said nozzle-height-adjusting mechanism comprising an adjustable wheeled crank shaft for supporting the cleaner, a plate sector operatively mounted on the cleaner and having a plurality of spaced seats adapted to engage the wheeled crank shaft for adjusting the nozzle in its optimum position for a particular surface covering, a feeler pivotally connected to the cleaner and to the plate sector and adapted to engage a surface covering over which the cleaner is propelled, means for limiting the movement of the feeler and the plate sector, resilient means connected to the feeler for exerting a tension to draw the feeler downwardly into contact with an underlying surface covering, resilient means for exerting a tension to draw the wheeled crank shaft rearwardly, a ratchet and pawl mechanism mounted on the cleaner including an eccentric connected to the crank shaft through a lost-motion connection whereby upon movement of the eccentric in one direction the crank shaft is moved out of engagement with the plate sector permitting the feeler to engage the surface covering and upon movement of the eccentric in the opposite direction the feeler is returned to its original position and the nozzle is automatically adjusted to its optimum position, means for actuating the eccentric including a foot-operated lever adapted to release the handle of the cleaner from its storage position permitting the handle to be placed in its working range, said ratchet and pawl mechanism being connected to said handle so as to be actuated upon propelling the cleaner to and fro by movement of the handle in its working range returning the foot-operated lever to its initial position and actuating the lost-motion connection permitting engagement of the crank shaft with the plate sector and adjustment of the nozzle height and withdrawal of the feeler from engagement of the surface covering.

6. A suction cleaner comprising; a body including a nozzle; supporting means carried by said body for supporting said body for movement over a surface to be cleaned; said body and supporting means being connected for movement relative to each other to position said nozzle at selected distances from said surface; means for locking said body and supporting means against movement relative to each other with said nozzle at varying distances relative to said supporting surface; a handle movably attached to said body for propelling said body over said surface; latch means for positively locking said handle in an upright storage position; manually actuatable latch release means movably mounted on said body and engageable with said latch means and operable to release said handle for movement from its vertical storage position and means cooperating with said latch release means, with said locking means and with said supporting means and operable upon actuation of said latch release means to latch releasing position to release said locking means, to move said supporting means relative to said body and to position said locking means in a selected position to select the final relative position of said supporting means and body and means for again moving said supporting means and body relative to each other to move said nozzle to said selected position above said surface and to relock said locking means.

7. A suction cleaner comprising; a body in-

cluding a nozzle; wheels for supporting said body for movement over a surface being cleaned; adjustable means for attaching said wheels to said body for movement relative thereto for positioning said nozzle in selected positions relative to said supporting surface; releasable locking means for locking said adjustable means in various adjusted positions; adjusting means for setting said adjustable means in adjusted position; gauging means for preselecting the setting of said adjusting means; a handle movably attached to said body for propelling said body over said surface; latch means for positively locking said handle in a vertical storage position; manually actuatable latch release means movably mounted on said body and engageable with said latch means and operable to release said handle for movement from its vertical storage position and means connecting said latch release means with said wheel adjusting means, said locking means and said gauging means and operable upon movement of said latch release means to latch releasing position to release said locking means, to move said wheels relative to said body and to move said gauging means into contact with said surface to preselect the setting of said wheel adjusting means and means for moving said adjustable means to the preselected position.

8. A suction cleaner comprising; a body including a nozzle; wheels for supporting said body for movement over a surface with said nozzle positioned at a selected distance above said surface; attaching means for movably securing said wheels to said body; a handle movably attached to said body for propelling said body over said
